UNITED STATES PATENT OFFICE.

JOHN MARTELL, OF NEW YORK, N. Y.

PICK HOLDER FOR FRETTED MUSICAL INSTRUMENTS.

Application filed January 18, 1924. Serial No. 638,947.

To all whom it may concern:

Be it known that I, JOHN MARTELL, citizen of the United States of America, residing at New York city, county and State of New York, have invented new and useful Improvements in Pick Holders for Fretted Musical Instruments, of which the following is a specification.

My invention relates to a pick holder attachment for fretted musical instruments and has particular application to banjos, mandolins, and ukuleles.

The small flat member of ivory, horn or metal known as a plectrum or pick and used for picking or striking the strings of an instrument, often becomes lost or broken during a performance and several measures may be dropped before a new pick is brought into use. It is the purpose of the present invention to provide an attachment for fretted musical instruments, such attachment being adapted to contain a number of picks and to hold them within easy reach of the performer, who may simply slide a new pick out of the attachment in the event of an accident occurring to the one being used. I accomplish this purpose by providing a device, of the character hereinafter described, which is readily applicable to any suitable part of the musical instrument, and which is designed to yieldably embrace one or more picks of any size and weight ordinarily used for this purpose.

According to this invention, and its use in connection with a banjo, it has been found particularly advantageous to attach the pick holder to a bracket of the banjo head, so that in the event of a lost or broken pick the available supply is near at hand and another pick may be removed from the holder and placed in use with practically no perceptible loss in rhythm of the composition being rendered by the performer.

One embodiment of my invention is illustratively exemplified in the accompanying drawings, in which Figure 1, is a plan view of a portion of a banjo head and neck with my improved attachment applied thereto; Figure 2 is a fragmentary view of the banjo rim showing a pick holder being supported on a bracket; Figure 3 is a sectional view on lines 3—3 of Figure 2; Figure 4 is a substantially vertical section taken on lines 4—4 of Figure 2; Figure 5 is a view of a neck portion of a differently fretted instrument

such as might be used in a mandolin or ukulele, the pick holder being attached to the peghead of the instrument; Figure 6 is a side view of the peghead shown in Figure 5 and Figure 7 is an end view of the same.

Referring to the drawings and particularly to Figures 1 to 4, inclusive, 10 designates a banjo head having the usual arm or neck 11 inserted in a rigid rim 12, the rim 12 being provided, in the usual manner, with a series of brackets 13.

Supported on one of the brackets 13 and arranged radially of the head 10 is a pick holder attachment 14 comprising the present invention. The holder is removably attached to the selected bracket 13 by means of a clamping device 15 which comprises a pair of plates having their end portions 16 curved or grooved to provide substantially circular gripping surfaces, one of which is adapted to embrace the mid-portion of the bracket 13, while the other grooved grip receives and supports the holder proper. The two plates of the device are clamped about the bracket 13 and holder 14 by adjustment of a clamp screw member 18 carried by one of the plates and having the head seated against the other plate, as clearly illustrated in figure.

As stated, one groove 16 of the clamp 15, embraces the stem 19 of the holder 14, the stem being a short length of material bent upon itself to form a channel portion, which is adapted to yield slightly when the clamp is adjusted to provide a more effective engagement of the two members. Beyond the stem 19 the holder is bent at an angle to form a rigid bracket 20 which is disposed over the head 10 and in a slight upward inclination to the plane of the head 10. The free end of the portion 20 is splayed to provide two rigid fingers 22 overlying the head of the instrument, as shown in Figure 1, and attached to the bracket 20 is a flexible, angular supporting metal piece 24, one arm of which is integrally attached to the lower portion of the bracket 20 at the inner face thereof, while the other arm is held substantially parallel to the upper portion 21 and arranged to exert a yieldable pressure against the under surface of the fingers 22. One or more picks 23 inserted between the rigid fingers 22 and the flexible arm 24 may

be readily removed one at a time by placing

the thumb and first finger against the portion of the pick between the fingers 22 and the under surface of the flexible arm and then drawing the pick away from the holder.

5 In the modification of the pick holder illustrated in Figures 5 to 7, inclusive, the peghead 24 of the instrument is used to support the attachment which comprises a substantially U-shaped rigid member 25, one 10 arm of which projects under the peghead 24 and is provided with an opening to receive a wood screw 26, the latter being adapted to project through a number of spacing washers 27 and into the under face 15 of the peghead. It is preferable to attach the holder over the end of the peghead, as illustrated in Figures 5 and 6, but it will be perfectly apparent however that the holder may be affixed to any other suitable part of 20 the head as well. Referring again to the specific construction of the member 25, the closed end of the latter bridges the end of the peghead and supports the overhanging upwardly inclined splayed arm 28 which 25 corresponds with the fingered portion of the bracket 20 of the preferred form. The flexible angle piece 29 is integrally attached to the inside surface of the closed end of the U-shaped member 25 and is arranged so 30 that the free arm yieldably engages, supports the picks and holds them against the under face of the splayed arm 28.

The latter construction is preferably used in connection with mandolins, ukuleles and 35 similarly constructed instruments, while the preferred construction shown in Figures 1 to 4 is designed to be used especially with banjos, but it will be noted particularly in connection with both modifications that the 40 holder may be adjusted with respect to the instrument and that the adjustment is practically vertically in both forms of application. As illustrated in Figure 2 this adjustment is effected by means of the clamp member 15. By releasing the screw 18 the clamping action is relieved and either the bracket 20, clamp 15, or both may be adjusted with respect to the bracket 13 supporting the attachment. This adjustment is 45 made necessary by the varying widths of rims 12. According to the construction shown in Figure 6 this same adjustment is made by increasing or reducing the number of spacing washers 27, the adjustment in the latter case being necessary because of the 50

different thicknesses of material used in pegheads.

Following proper adjustment of the pick holding attachment to the instrument and the placing of the picks between the rigid and flexible arms of the holder, it is a very simple matter, in the case of a pick becoming broken or lost during a performance, for the musician to reach over the head of the instrument and withdraw another pick from the holder. 60 65 65

What I claim and desire to secure by Letters Patent is:—

1. A pick holder attachment for fretted musical instruments, comprising a rigid 70 supporting bracket, and separate yieldable means carried by the bracket and normally contacting therewith for yieldably holding a pick against the bracket and over the head of the instrument. 75

2. A pick holder attachment for fretted musical instruments comprising a rigid supporting bracket, and a yieldable plate attached to the bracket normally contacting therewith and underlying a portion thereof, whereby a plurality of picks may be held between the bracket and the plate and over the head of the instrument. 80

3. A pick holder attachment for fretted musical instruments, comprising a rigid 85 angular bracket for attachment to the instrument, and an angular spring plate having one flange attached to the bracket adjacent the angle thereof and the other flange underlying the portion of the bracket beyond the angle. 90

4. A pick holder attachment for fretted musical instruments, comprising a rigid angular bracket for attachment at one end to the instrument, the other end being disposed over the head of the instrument and having a splayed free end portion, and an angular spring plate having one flange attached to the bracket adjacent the angle thereof and the other flange yieldably engaged against the under surface of the free end and projecting to a point short of the ends of the overlying splayed portion of the bracket. 95 100

5. In combination, a pick holder attachment for fretted musical instruments, and means for detachably and adjustably supporting the holder on the instrument. 105

In testimony whereof I affix my signature.
JOHN MARTELL.
